(57) **CLAIM**

The ornamental design for an ironing board cabinet, as shown and described.

DESCRIPTION

FIG. 1 is a front elevation view of an ironing board cabinet showing my new design;

FIG. 2 is a rear elevation view;

FIG. 3 is a left side elevation view;

FIG. 4 is a right side elevation view;

FIG. 5 is a top plan view;

FIG. 6 is a bottom plan view;

FIG. 7 is a left side isometric view; and,

FIG. 8 is a right side isometric view of an Ironing Board cabinet with a front door in open position.

The broken lines shown in FIG. 8 are for illustrative purposes only and form no part of the claimed design.
